FLUE-GAS-RECIRCULATION SYSTEM FOR SHELL STILLS

Application filed February 16, 1928. Serial No. 254,793.

The present invention relates to oil refining apparatus, and particularly to refining or topping stills of the shell type, and aims to improve the efficiency of such apparatus by providing for the recirculation of a portion of the flue gases in such a manner as to not only increase the area of the heat exchange surfaces but also the refining capacity of apparatus of this type.

10 It is also sought to devise a still construction of this character in which this increased efficiency is effected along with an increase in fuel economy due to the recirculation feature, and at the same time the danger of injury to the still structure on account of so-called "hot spots" is practically eliminated.

15 In carrying out these objects of the invention, it is further sought to provide apparatus of such character as to improve generally shell still constructions for which the invention is especially adapted.

With the foregoing general objects in view, the invention will now be described by reference to the accompanying drawings illustrating one form of furnace and shell still construction which is adapted for the embodiment of my improvements, after which those features and combinations deemed to be novel will be set forth and claimed.

20 In the drawings:—

Figure 1 is a plan view showing a portion of a still battery embodying the herein described flue gas recirculating system;

Figure 2 is a side elevation, partly broken away and in vertical section;

Figures 3 and 4 are views in rear and front elevation, respectively;

Figure 5 is an enlarged detail view illustrating the interior of one of the recirculating flues; and

Figures 6 and 7 are end views of one of the recirculating flues, showing two different forms of ribs or fins for dividing the flow of flue gas.

45 In the drawings is illustrated a common form of shell still unit 10, usually arranged in battery form with each unit 10 overlying a furnace or combustion chamber 11 using either a solid fuel, or oil or gas, as in 50 the illustrated apparatus, this fuel being

supplied by way of a burner opening 12. The air for supporting combustion in the illustrated construction is admitted through an intake opening 14 into a bottom chamber 15, and thence through checker openings 16 into the combustion chamber 11, from which the waste flue gases are conducted out through a furnace flue passage 17 to a tunnel 18, and thence to a stack (not shown).

Where a series of such stills are operated as a continuous battery, those still units in which the final fractions are taken off from the crude oil must be operated at a comparatively high temperature, resulting in flue gas temperatures of around nine hundred degrees Fahrenheit; whereas, in the stills at the opposite end of the battery, where the first fractions are removed, a lower oil temperature is required to be maintained, but nevertheless these stills are also fired at a rate to produce a flue gas temperature around nine hundred degrees Fahrenheit. The reason for this lies in the fact that excess air is employed for the purpose of maintaining relatively short flames low in carbon dioxide (CO_2), so as to avoid contact between the flame and still bottom, and thereby reducing as much as possible the formation of hot spots which always follow rapidly the accumulation or deposit of carbon, at low temperature end of the battery especially. But this excess air must be heated, and hence the excessive firing and fuel consumption for that purpose at low temperature end of the battery. Even so, the firing can only be carried on within certain limits, because of this danger of hot spots, and such limitation in firing temperature likewise limits the capacity of the still.

These inefficient characteristics inherent in the operation of shell stills have long been recognized and have resulted in the gradual abandonment of this type in favor of the more efficient tube still, wherever new installations are being made. However, a vast number of shell still installations are yet being operated, as they represent an enormous investment, too great either to abandon or to convert over into the tube form of still. It is the purpose of the present invention to

render these shell types of installations very much more efficient, and this I have found to be possible by the simple expedient of substituting for the excess air employed in the combustion chamber a certain amount of recirculated flue gases, for the reason that the recirculation of such gases is practicable and feasible where provision can be made to effect a greater percentage of heat transfer from the combustion gases to the contents of the still by convection or rubbing contact with the heat exchange surfaces than ordinarily takes place in the usual shell still construction through the medium of its bottom surface alone. If the necessary additional heat exchange surface can be incorporated into this old shell type, and a further safety factor introduced for blanketing and tempering the hot combustion gases directly beneath the still bottom, it will be understood that the results sought after in this connection may be accomplished.

With this end in view, each flue passage 17 is provided with a gate damper 20, and at some point along the flue gas tunnel 18 connection is made for each battery, as by a bend or elbow 22, with a suction fan 24 for pulling a certain volume of the hot flue gases from the tunnel 18 and discharging the same into a header conduit 26, as clearly shown in Figures 1 to 3. From the header 26 connection is made by means of branch conduits or pipes 28 with a series of flue pipes 30, preferably two pairs of such flue pipes for each still unit 10, these flues 30 extending longitudinally through the still, and at points not interfering with the manholes 31 and at some distance above the bottom of the still so as to afford access thereto for cleaning purposes. At the front end of each still, return bends 32 are connected with the ends of the flue pipes 30 for reconducting the flue gases to the combustion chamber 11 into which the recirculated gas is discharged through a passage 34 located near the top of the chamber 11 and above the peephole 35 usually provided at the front of the furnace.

A suitable damper 36 is provided in the elbow 22 of each battery, and a damper 37 is located in each of the branch pipes 28, for facilitating the proper regulation of the flow of the gases; and a cable 38 and suitable counterweight 39 may also be provided for facilitating the regulation of each of the dampers 20 above referred to (see Figure 3).

With such an arrangement, it will be seen that each still unit has a dampered communication with the flue gas passages 17-18, and by control of the dampers the flue gases can be recirculated through any one or more of the still units at will, and the extent or volume of the flow conveniently regulated to any desired degree.

On account of the length of the stills, ranging from thirty to forty feet, the tubes 30 will

ordinarily be of comparatively large diameter, or from six to twelve inches, hence with flues of this size, without other provision, there would probably be a loss in efficiency of heat transfer on account of the large core of gases traveling axially through the flue without coming in contact with the interior surface thereof. I therefore contemplate using a hollow core tube 40 (Figure 5) closed at each end by the preferably tapered terminals 41, each core tube being of smaller diameter than the flue, whereby the recirculated flue gases are caused to travel through the annular space between the flue and its core. Each core is maintained properly spaced centrally within the flue by means of longitudinal ribs or fins 42 (Figure 6) by which the flow of gases is split or divided, and these may be obliged to follow a still longer course through the flue by substituting ribs or fins of helical outline as illustrated at 42' in Figure 7.

By means of the above described recirculating arrangement, it will be seen that the flue gases which are returned to the combustion chamber 11 through the passages 34 are utilized in place of the excess air ordinarily used, and since these gases are still relatively hot their use represents a clear gain in fuel economy as represented by the difference in temperature of such gases and that of the atmospheric air it replaces. The discharge of the recirculated gases into the upper portion of the combustion chamber produces a tempering or blanketing effect upon the combustion gases, and thus protects the bottom of the still to such an extent as to practically eliminate the danger of hot spots, and the rate of firing can be increased without danger to the still bottom. This increased firing rate is of course desirable in the interest of greater still capacity, and furthermore is made practicable and feasible by the increased heat transferring capacity afforded by the convective heating surface of the flues 30. The displacement of excess air by the recirculated flue gases also works out in the interest of increased firing rate because of the higher percentage of CO_2 in the fresh combustion gases and resultant higher flame temperatures. But as the increase in the amount of heat evolved is offset by the increase in the rate of heat transfer through the medium of the flues 30 and the extensive area of convective heating surfaces there provided, this means an increase in still capacity which does not impose any increased or excess burden upon the bottom heating surface of the still.

An additional advantage in the improved construction resides in its adaptability to continuous battery stills in "rerun" operations, in which the necessity of direct firing can be dispensed with in connection with those units which are fired only very lightly, since the fairly hot recirculated flue gases will afford

the requisite heating capacity in lieu of such direct firing. This is a distinct economical gain, especially since it is well known that direct firing is always a comparatively inefficient process where the rate of firing has to be kept low. The selective regulation provided in the apparatus herein described not only makes such indirect firing operation possible, but permits such convenient adjustment of the operation of the different stills of the same battery as may be desirable. Again where the particular stills of the same battery all require to be fired at the same rate, the increase in the heat transfer capacity by means of the flue structure herein described makes possible a lower firing rate for the same still capacity, or if the former firing rate be maintained the still capacity will be increased; hence, if the former rate of firing is injurious to the still, the improved flue gas recirculating system will provide the means for eliminating such injury without any loss of capacity.

It will thus be apparent that I have devised a practical and efficient arrangement and construction for fulfilling all the desired objects of the invention, and it is equally apparent that the construction or arrangement of the system can be altered in any desired or required way to meet varying conditions of operation, and is in no sense to be limited to details herein illustrated; accordingly, I desire to reserve the right to make all such changes or modifications as may fairly fall within the scope of the appended claims.

Having thus described my invention, what I claim and desire to secure by Letters Patent is:—

1. Flue gas recirculating apparatus for oil refining shell stills comprising, in combination with a furnace combustion chamber and an oil refining still of the tubeless shell type overlying said chamber, one or more flues extending through said still, and means for conducting a portion of the waste flue gases from the combustion chamber, through said flues and thence back into the combustion chamber.

2. Flue gas recirculating apparatus for oil refining shell stills comprising, in combination with a furnace combustion chamber and an oil refining still of the tubeless shell type overlying said chamber, one or more flues extending through said still, and means for conducting a portion of the waste flue gases from the combustion chamber, through said flues and thereafter discharging the same into the space within said combustion chamber directly underlying the bottom of the still.

3. Flue gas recirculating apparatus for oil refining shell stills comprising, in combination with a series of furnace combustion chambers, an oil refining still of the tubeless shell type overlying each of said cham-

bers, a flue gas header provided with means for diverting a portion of the combustion gases issuing from said chambers, one or more flues extending from said header through each of said stills, means communicating with said flues for reconducting gases from said flues to the combustion chambers, and damper means for selectively regulating the recirculating flow of said gases through the flues.

4. Flue gas recirculating apparatus for oil refining shell stills comprising, in combination with the combustion chamber and a still overlying said chamber, a tube extending through the still, a core structure in said tube and forming an annular passage there-through, and means for conducting a portion of the waste combustion flue gases from the combustion chamber into said flue passage and thence back into the combustion chamber.

5. Flue gas recirculating apparatus for oil refining shell stills comprising, in combination with the combustion chamber and a still overlying said chamber, a tube extending through the still, a core extending axially through said tube and forming an annular passage, and means for conducting a portion of the waste combustion gases from the combustion chamber into said annular passage and thence back into the combustion chamber.

• In witness whereof I hereunto affix my signature.
